UNITED STATES PATENT OFFICE.

ALDEN S. BOYER, OF CHICAGO, ILLINOIS, ASSIGNOR, BY MESNE ASSIGNMENTS, TO
ALBERT G. McCALLEE, OF CHICAGO, ILLINOIS.

INSOLE.

1,144,291.

Specification of Letters Patent. Patented June 22, 1915.

Application filed June 12, 1912. Serial No. 703,107.

To all whom it may concern:

Be it known that I, ALDEN S. BOYER, a citizen of the United States, and resident of Chicago, in the county of Cook and State of Illinois, have invented a certain new and useful Improvement in Insoles, of which the following is a full, clear, concise, and exact description, reference being had to the accompanying drawings, forming a part of this specification.

My invention relates to insoles to be worn as auxiliary linings in boots and shoes and has for its object provision of an insole suitably medicated to relieve excessive perspiration of the feet and to toughen the same.

Broadly, the distinctive feature of my invention lies in the fact that a medicinal agent is applied to an insole of felt or other suitable material. The medicinal agent, which I shall hereinafter take up, is one which, when it comes in contact with the perspiration, sets free nascent oxygen which is a deodorizer.

I sometimes find it desirable to cut the edges of an insole of this kind to make it fit a shoe smaller in size than the size shoe for which the insole was originally intended. To facilitate the cutting I provide lines upon the insole of my invention to indicate the various sizes. The lines may or may not be marked to show what size is had by cutting along a certain line. I have not thought it necessary to mark the lines on the drawing accompanying this application.

My invention will be more clearly understood by referring to the accompanying drawings, in which—

Figure 1 is a face view of an insole of my invention; Fig. 2 is an enlarged section of a portion thereof; and Fig. 3 is a cross-sectional view of a portion of a modified form of insole.

In preparing my insole I prefer to use white felt, although it is obvious that other materials might be substituted for the felt without departing from the spirit of my invention. I prefer to treat the felt insole indicated at A in Fig. 1, with a mixture of zinc peroxid and perborate of soda. Either of these chemicals may be used alone with good results. The medicinal agent is applied to both sides of the felt and the excess removed with a roller. The interstices between the fibers of the felt are filled with the mixture referred to as indicated at B in

Figs. 2 and 3. After the insole has been treated with the medicinal agent, I prefer to apply a mixture of glue and shellac to one side of the insole. The glue and shellac serve to stiffen the insole, to cement the same to the shoe, and to retain the zinc peroxid, perborate of soda, or the mixture of these two, in the interstices of the felt. I sometimes add the glue and shellac to the zinc peroxid, perborate of soda, or the mixture of these two before they are applied to the insole.

As is well known, the perspiration of the human body contains a considerable proportion of uric acid. When the uric acid of the perspiration comes into contact with the zinc peroxid, it reacts with the same to form oxid of zinc and to set free nascent oxygen. As I have said before, the nascent oxygen acts as a deodorizer. The zinc oxid which remains is a healing agent which is very beneficial in cases where the feet are afflicted with corns, bunions, chafing or the like. In a like manner the perborate of soda reacts with the uric acid to set free oxygen and form borax.

In Fig. 3 I have shown a section of a portion of an insole provided with a backing C of suitable stiffening material, such as hair cloth or the like. I find, however, that this backing is not absolutely necessary as the mixture filling the interstices of the material together with the glue and shellac serve to impart the necessary stiffness to the same. At D in Fig. 1 I have shown lines to facilitate cutting a smaller size insole from an insole of larger size. These lines are applied in any approved manner. The insole shown in the drawing is especially adapted to be worn in a lady's shoe.

It is difficult if not impossible to give the actual chemical reactions which take place when the acids of the perspiration come into contact with the zinc peroxid or sodium perborate with which the insole is treated. One thing is certain, however, in either case nascent oxygen is released, and in the case of zinc peroxid zinc oxid is left as a result of the reaction or reactions which occur.

What I claim and desire to secure by Letters Patent is:

1. An insole comprising a piece of suitable material impregnated with zinc peroxid.

2. An insole comprising a piece of felt, and zinc peroxid in the interstices of the felt.
3. An insole comprising a piece of felt, and a mixture of zinc peroxid, glue and shellac filling the interstices of the felt.
4. An insole of suitable material impregnated with a medicinal agent adapted to react with the uric acid of the perspiration to set free a deodorizing agent.
5. An insole of suitable material impregnated with a medicinal agent adapted to react with the uric acid of the perspiration to form a healing agent and to set free a deodorizing agent.
6. An insole of suitable material impregnated with a medicinal agent adapted to react with the perspiration to set free oxygen.
7. An insole comprising a piece of suitable material impregnated with a medicinal agent adapted to react with the perspiration to form a healing agent.

In witness whereof, I hereunto subscribe my name this 5th day of June, A. D., 1912. 25

ALDEN S. BOYER.
